UNITED STATES PATENT OFFICE.

LESTER R. WELLMAN, OF CHICAGO, ILLINOIS.

DESIGN FOR A PLATE FOR LIGHTING FIXTURES.

Application filed May 24, 1928. Serial No. 26,835. Term of patent 3½ years.

To all whom it may concern:

Be it known that I, LESTER R. WELLMAN, a citizen of the United States, residing at Chicago, in the county of Cook and State of Illinois, have invented a new, original, and ornamental Design for a Plate for Lighting Fixtures, of which the following is a specification, reference being had to the accompanying drawing, forming part thereof.

Fig. 1 is a plan view of a plate for lighting fixtures, showing my new design. In this

figure only a portion of the ornamentation is shown completed, it being understood that the remainder of the plate within the marginal outline involves a mere repeat of the ornamentation more fully illustrated.

Fig. 2 is a side elevation of the same.

I claim:

The ornamental design for a plate for lighting fixtures, as shown and described.

LESTER R. WELLMAN.
